DISPENSING PUMP

Ernest W. Shugart, Kalamazoo, Mich.

Application April 21, 1933, Serial No. 667,177

8 Claims. (Cl. 221—103)

This invention relates to improvements in dispensing pumps for lubricating oil.

The objects of the invention are:

- First, to provide an improved pump construction in which the delivery of the oil will be conspicuous and visible for the satisfaction of the consumer.
- Second, to provide an improved pump structure and operating gear for such a pump.
- 10 Third, to provide an improved electrically driven pump.

Fourth, to provide such a pump which can be readily adjusted to exactly calibrate the same.

- 15 Fifth, to provide such a pump which will effectively deliver one quart or a multiple number of quarts by successive action of the piston.

Sixth, to provide in such a pump an improved nozzle construction which will effectively cut off the discharge at the nozzle tip.

- 20 Seventh, to provide such an arrangement or construction in which the motor can be controlled by connections at the nozzle.

- 25 Further objects and objects pertaining to details and economies of my invention will appear from the description to follow. The invention is defined and pointed out in the claims.

I accomplish the results of my invention by the preferred embodiment of pump illustrated in the accompanying drawings, in which:

- 30 Fig. 1 is a plan view of a pump embodying the features of my invention.

- Fig. 2 is a detail slightly reduced end elevation from the left-hand end of Fig. 1, a portion of the casing being broken away to show 35 details and the delivery pipe and electric switch connection being shown in sections.

- Fig. 3 is a detail vertical slightly reduced sectional elevation taken on a line corresponding to line 3—3 of Figs. 1, 2 and 4, parts of the 40 mechanism being shown in full lines.

Fig. 3A is a vertical section on line 3A—3A of Fig. 3 showing details of the pump piston and the manner of adjusting it.

- Fig. 4 is an enlarged detail sectional plan 45 through the pump cylinder taken on line 4—4 of Figs. 2 and 3.

Fig. 5 is an enlarged detail vertical sectional view through the improved nozzle taken on line 5—5 of Fig. 2, portions being in full lines.

- 50 Fig. 6 is an enlarged detail sectional elevation taken on line 6—6 of Fig. 2.

Fig. 7 is an enlarged detail transverse sectional view on line 7—7 of Fig. 1 showing details of the clutch mechanism.

- 55 Fig. 8 is an enlarged detail transverse sectional

view on line 8—8 of Fig. 3, showing the details of the cross head and the pitman and coupling rod connection.

Fig. 9 is an enlarged detail vertical sectional view on line 9—9 of Fig. 3, showing details of the check valve structure.

Fig. 10 is a detail sectional elevational view on line 10—10 of Fig. 3, showing details of the control.

Fig. 11 is a detail sectional elevation on line 10 11—11 of Fig. 1 of the electric motor.

Fig. 12 is a detail sectional view on line 12—12 of Fig. 3 showing details of construction.

Fig. 13 is a detail sectional view on line 13—13 of Fig. 1, showing the connection of the driving pinion to the driven gear.

The parts will be identified by their numerals of reference which are the same in all the views.

1 is the base casting carrying the remaining parts. It has an upright portion 2 which constitutes a shell-like casing and terminates in the pump cylinder base 3. This is extended into a platform 4 at the bottom which carries the electric motor 5 which has an internal reduced gear structure connected for driving the pump.

6 is the pump cylinder of glass, having a head 7 with a delivery pipe 8 connected to flexible hose 9 terminating at the nozzle 10. The head 7 is flanged at 71 to embrace the end of the cylinder 6 and is provided with a suitable gasket ring 72. A flange 31 surrounds the cylinder base and receives the lower end of the glass pump cylinder 6 and is provided with a gasket 32. The pump cylinder is retained in place by cap screws 73 entering through suitable ears 74 on the head 7 and extending into ears 33 on the base 3—see Figs. 1, 2 and 3.

The pump is a single acting pump discharging on the up-stroke. It has a hydraulic piston head 11 with the usual hydraulic packings and check valves 12—see Fig. 3.

The piston rod 13 extends through stuffing box 14 and is connected to crosshead 15 by the cross pin 16 in any well known way. The crosshead 15 reciprocates in ways 17 which are cast integrally with the shell 2. Detachable flanges 171 embrace the edges of the crosshead 15.

A boss 18 is cast integrally with the casing 2 and contains a journal bearing 181 in which is supported a journal pin 19 to which is secured the driven gear 20.

On the driven gear 20 is the adjustable wrist pin 21 to which is connected the pitman 22. This

is made eccentric to its shank 211 which extends through the said driven gear 20 and is clamped thereto by the clamping nut 23 as seen detailed in Fig. 6. The end of the shank 211 is slotted 5 at 212 for a screw-driver or wrench whereby the wrist pin 21 is adjustable because it is eccentric to the said shank 211.

The gear 20 is driven by the pinion 24 on the driven shaft 25 of the electric motor 5—see 10 Fig. 13. On the shaft 25 is a slipping spring clutch 26 of usual construction. From this it will be seen that when the pump is actuated by the motor, it will be actuated by the motor driving the shaft 25 which through the friction clutch 15 26 drives the pinion 24 which, being in mesh with the gear 20 through pitman 22, actuates the piston rod 13 and thus operates the pump.

On the up-stroke of the pump, it discharges 20 through the pipe 8 into the delivery spout 9. The cut-off valve 10 is especially constructed. 91 is the cylindrical end of the pipe carrying the fixed collar 92. The end is plugged at 93 and there are lateral discharge openings 94. A hollow valve member 101 is provided with a stuffing 25 box 102 which is adapted to reciprocate on the cylindrical portion 91 of the pipe. This part is internally screw-threaded at 103. 104 is an adjustable sleeve screw-threaded within the member 103 with the cylindrical bore 105 adapted 30 to reciprocate over the collar 92. This is provided with a central discharge aperture 106, and is flanged at 107 to embrace and coact with the plug 93 to complete the cut-off valve. This is held yieldingly in place by the compression spring 35 108 reacting against the collar 92 and the top end of the valve member.

The motor 5 is provided with a switch 51 to 40 which is connected a Bourdon tube 52 extending to lever 53 fulcrumed at 54 on the side of the pipe 9 whereby the motor is under instant control by the operator when he is delivering oil at the nozzle. He does not need to cut off the motor at precisely the right point because when he cuts off the oil, the slip clutch will permit the motor to run without any effect on the pump.

Secured to the shaft 19 is the driving pinion 27 which drives the control gear 28 which is journaled on pin 29. This gear 28 is provided 50 with a perforation 30 to receive the spring pressed stop pin 31. The spring pressed stop pin 31 is carried in socket 32 on the outer end of the arm 33 which is also pivoted on the pin 29.

A face plate 34 embraces the face of the gear 55 28 and is provided with a series of holes 35 through which the stop pin 31 may be projected. The pin 31 is provided with a knob 31' by which it can be withdrawn from the apertures 35 and adjusted to any point desired and 60 allowed to project yieldingly through any of the apertures 35.

The control wheel 28 will travel until the hole 30 is brought opposite the pin 31 when it will snap in and stop the pump. This gear 28 is of such 65 ratio and is so timed that an evolution of the pump will occur while the gear 28 is moving one interval. Thus if the user desires to pump and deliver one quart to the consumer, he sets the pin 31 one notch ahead. If it is desired to pump 70 and deliver two quarts, it is set ahead two intervals. If a gallon or four quarts is desired, four intervals. The operator in delivering lubricant sets the pin ahead one interval for one quart, two intervals for two quarts, and the pump 75 automatically pumps that much. The motor slips

on its slip clutch until the valve 10 is opened. When that valve is opened, the pump can run until the valve is closed again or until the pump is stopped by the stop pin 31. When the pump is stopped by either means, the clutch slips and the motor is allowed to run until the cut-off lever 53 is operated and stops the motor.

The pump is placed upon the head of an oil drum 39. The intake pipe 40 leads up to connection 41 to the base of the pump. A check 10 valve 42 cooperates with the pump. It consists of a casing 43 with a lid valve 44 held to place by the usual spring 45—see Fig. 9.

I show a gear 46 for a counter device secured to the back of the gear 28 geared to drive the 15 pinion 47 of the counter 48 to operate the counter. As my invention does not pertain to the counter, I have not detailed it.

I provide a slotted head 49 on the shaft 19 for a crank connection to operate the pump in 20 case of power failure.

While I have described my improved pump as a pump for dispensing oil, it is adapted for use wherever it is desired to dispense liquid, and whether it be of quart size or larger or smaller 25 is not important.

Having thus described my invention, what I claim as new and desire to secure by Letters Patent, is:

1. In a dispensing pump structure, the combination of a suitable base, an electric motor with a reducing gear mounted thereon, a supporting frame on said base with a pump cylinder base formed thereon, a pump cylinder with discharge at its upper end and with intake at its 35 lower end, a hydraulic piston therein with suitable pump check valve, a piston rod with cross-head cooperating with said pump piston, a gear with pitman connection for actuating said pump piston, a slip clutch between the said gear and 40 the said motor, a discharge pipe from the said cylinder with spring closed cut-off valve, and an operating lever carried by the discharge pipe with connection to control the switch of said motor whereby the amount of oil fed can be 45 controlled at the nozzle by the stopping of said motor.

2. In a dispensing pump, the combination with a delivery pipe, an automatic cut-off valve therefor comprising a cylindrical portion at the end 50 of said pipe with lateral openings, a stop collar thereon, a cross plug across the end, a reciprocating valve member with central discharge aperture and flanged to close against the plugged end of said pipe, and a spring within the said 55 cylindrical part reacting against the said stop collar to hold the valve yieldingly in closed position, as specified.

3. In a dispensing pump structure, the combination of a cylinder, a piston in said cylinder, 60 an electric motor means for driving the same, a slip clutch connection in the drive of said pump, a discharge pipe from said pump, an automatic spring closed cut-off valve at the discharge pipe adapted to be opened against pressure and close 65 automatically, and an automatic means to stop the said pump for measuring the amount dispensed by said pump.

4. In a dispensing pump structure, the combination of a cylinder, a piston in said cylinder, an electric motor means for driving the same, a slip clutch connection in the drive of said pump, a discharge pipe from said pump, an automatic spring closed cut-off valve at the discharge pipe 70 adapted to be opened against pressure and close 75

automatically, and a means to stop the said pump for measuring the amount dispensed by said pump.

5. In a dispensing pump structure, the combination of a cylinder, a piston in said cylinder, an electric motor means for driving the same, a slip clutch connection in the drive of said pump, a discharge pipe from said pump, an automatic spring closed cut-off valve at the discharge pipe 10 adapted to open under pressure and close automatically, and means to stop the said pump comprising a rotary disk gear driven by the gearing of said pump containing a stop pin aperture, an adjustable spring pressed stop pin associated 15 therewith and adjustable in the path of said stop pin aperture, and a control plate in front of said disk gear with apertures at intervals to receive the said adjustable spring pressed stop pin to engage the said stop pin aperture in said disk at pre- 20 determined points to permit the actuation of the pump to the desired extent for measuring the amount dispensed by said pump.

6. In a dispensing pump structure, the combination of a cylinder, a piston in said cylinder, an 25 electric motor means for driving the same, a slip clutch connection in the drive of said pump, a discharge pipe from said pump, an automatic spring closed cut-off valve at the discharge pipe adapted

to open under pressure and close automatically, and a means to stop the said pump comprising a rotary member driven by the said pump with a stop member means associated therewith, a control plate in front of said movable member, and an adjustable stop carried thereby to cooperate with the movable stop member to stop the pump at a predetermined point for measuring the amount dispensed by said pump.

7. In a dispensing means, the combination of a 10 delivery pipe with closed end and lateral openings, a cylindrical valve member embracing the end of said pipe in spaced relation thereto, a stuffing box between the said parts, a flanged valve member cooperating with the end of said pipe, and 15 spring means for holding the said valve yieldingly in position against the end of the pipe, as specified.

8. In a dispensing means, the combination with a delivery pipe having closed end with lateral 20 openings, of a cylindrical spring pressed valve member embracing said pipe in spaced relation and having a central opening at its end adapted to yield under pressure for the discharge therefrom and to close automatically when the pressure is relieved.

ERNEST W. SHUGART.
